No. 758,180.

PATENTED APR. 26, 1904.

M. HOFHEIMER.
COIN CONTROLLED VENDING MACHINE.

APPLICATION FILED APR. 4, 1903.

NO MODEL.

UNITED STATES PATENT OFFICE.

MAURICE HOFHEIMER, OF NEW YORK, N. Y., ASSIGNEE TO UNITED STATES VENDING CORPORATION, A CORPORATION OF MAINE.

COIN-CONTROLLED VENDING-MACHINE.

SPECIFICATION forming part of Letters Patent No. 758,180, dated April 26, 1904.

Application filed April 4, 1903. Serial No. 151,060. (No model.)

To all whom it may concern:

Be it known that I, MAURICE HOFHEIMER, of New York, in the county of New York and State of New York, have invented certain new and useful Improvements in Coin-Controlled Vending-Machines; and I do hereby declare the following to be a full, clear, and exact description of the invention, such as will enable others skilled in the art to which it appertains to make and use the same.

The object of this invention is to provide in a coin-controlled vending-machine improved means for ejecting the articles of merchandise for locking the cash-drawer and for detecting and throwing aside spurious slugs or coin.

A further object is to provide a vending-machine possessing many advantages in point of simplicity, durability, inexpensiveness, and certainty of operation.

The invention will be hereinafter fully set forth, and particularly pointed out in the claims.

In the accompanying drawings, Figure 1 is a view in side elevation with parts broken away and in section. Fig. 2 is a rear view, also with parts broken away. Fig. 3 is a sectional view of the castings removed from the casing. Fig. 4 is a view of the ejector. Fig. 5 is a view of the slug-detector. Fig. 6 is a detail.

Referring to the drawings, 1 designates the inclosing casing, wherein is mounted a frame or casting 2, having a flat shelf 3, above which are the merchandise-holding chutes 4, which may be of any desired number and of the same or different sizes, and they are preferably connected together by cross-pieces 5. In the drawings I have shown two supply-chutes and two corresponding ejectors; but as a matter of convenience only one need be described.

Beneath the supply-chute within the shelf is an opening 6, wherein a coin is designed to be held until the lowermost article with which it is in contact is ejected from the shelf, the width of such opening being slightly greater than the diameter of the coin. The latter is supported by a bevel-faced tooth 7 of an ejector-plate 8, such plate being adjustably secured

by a screw 9 on a push-rod 10, extended transversely through casting 2. The plate is guided in its movements by the side walls of opening 6. To the rear end of this push-rod is secured a right-angular finger 12, the upper horizontal portion of which is in line with shelf 3, with the result that the lowermost article is retained in proper position until ejected, the forward edge of the article being held against such finger by the coin resting on tooth 7. From the lower end of this finger projects a lug 13, which upon contacting with the rear of the casting serves as a stop to limit the return movement of the ejector and push-rod under the tension of a coil-spring 14. (Shown as secured at its rear end to finger 12.) From plate 8 extends a rib 15, which serves to prevent the coin from falling behind the ejector in case the push-rod 10 is forced forward too quickly. Normally the ejector-plate is about on the same vertical plane with the lower end of a beveled wall 16, extending upwardly from casting 2, and when pushed forward travels evenly in opening 6, as does also the coin; but when the article is free of the supporting-shelf the coin, being deprived of its forward support, will fall from the tooth 7.

17 designates a second frame or casting pivotally secured at its lower end to the front of casting 2. It is formed at about the center of its upper edge with a slot or cut-out 18 and flange 19, against which fits the lower edge of an inclosing door 20. This door at its center has a tenon 21, which fits within slot or cut-out 18, the door at its other end being secured to the casing by lock 22. Thus in order to gain access to the interior of the machine lock 22 must be first operated and the door moved, so as to lift its tenon from the hinged casting. In the front wall of this casting are coin-inlet openings 23, and immediately coincident with such openings are the ends of a plate 24, secured to the rear face of such wall. In this face are coin passage-ways which open immediately above the beveled wall 16, so that a coin deposited in these openings will fall from the passage-ways onto the beveled wall 16 and pass between the latter

and the lower front cross-piece 5, and thereby be directed onto the supporting-tooth of the ejector. I have shown beveled ribs 25 and 26 on the rear face of wall 16 to aid in guiding the coin, the ribs 26 also serving to guide the slugs away from the ejector-opening. Once a coin is guided into the ejector it is loosely supported between the side edges of the opening in the supporting-shelf and held 10 between the ejector-plate and the vendible article. These side edges in the supporting-shelf also serve to guide the ejector in its forward and rearward movements. When the pusher-rod is forced rearward, the coin and 15 article travel with it; but as soon as the article falls off of shelf 3 and the pushing-rod is released the coin being deprived of the support of the article immediately falls from the tooth into the cash-drawer 27. This cash-drawer is supported by opposite guideways 28 and is equipped with an inner shouldered lug 29, with which engages a pin 30, movable vertically in a boss 31 of casting 2. When the hinged casting 17 is in its normal position, a 25 lug 32 thereof is directly above pin 30, thereby preventing the latter from being raised out of engagement with the drawer-lug 29. To remove the cash-drawer, it is necessary to first turn the hinged casting forward and hold the 30 pin 30 elevated out of line of movement of the drawer-lug.

33 designates a magnetized rod secured to the under side of the overhanging portion of casting 17 by plates 34, which are preferably 35 made of non-magnetic material. The right-angular ends of this rod are about in line with the coin passage-way, so that upon the deposit of a spurious coin in the form of an iron or steel slug or washer the same instead of 40 jumping from the passage-way across to the beveled wall 16 will be attracted by the projecting end of the magnetized rod, around which it will partially revolve, as shown in Fig. 5, until by weight it drops therefrom to 45 one side of the wall 16 and rib 26, from whence it may fall into the cash-drawer without in any way engaging with the ejector.

The advantages of my invention are apparent. It will be seen that the parts are 50 extremely simple both in construction and operation. It will also be noted that the ejector is composed of but few parts, insuring the ejection of the merchandise by the presence of the coin and allowing the latter to fall by 55 its own weight once the merchandise is forced from the supporting-shelf.

I claim as my invention --

1. A coin-controlled vending-machine having a supporting-shelf formed with an opening, the width of the latter being slightly 60 greater than that of the coin, a coin-guideway for directing a coin into such opening, and an ejector comprising a spring-held rod, a plate carried thereby with its face normally in the

same plane as such guideway, said plate fitting 65 in said opening and having a support upon which the coin rests while being moved with the ejector longitudinally through the opening, and means movable with the ejector between which and the coin the article of merchandise is designed to fit, the retention of such coin on its support being dependent upon its engagement with such article of merchandise, as set forth.

2. A coin-controlled vending-machine having 75 a supporting-shelf formed with an opening, a spring-held rod movable transversely to the shelf, a plate secured on such rod having a tooth beveled on its upper face forming a support for a coin, said plate fitting in and guided 80 by said opening, and a finger carried by such rod and extending in line with said shelf, the article of merchandise being designed to fit between said finger and the plate, as set forth.

3. The combination with the casting having 85 a supporting-shelf formed with an opening, of a spring-held rod movable transversely through the casting, a plate secured on such rod having a tooth beveled on its upper face, said plate fitting in and guided by said opening, a finger carried by such rod extended in line with said shelf, the space between said finger and plate being designed to accommodate the articles of merchandise, and a stop 90 for limiting the return movement of said rod, 95 as set forth.

4. The combination with the casting having a supporting-shelf formed with an opening and a beveled wall, the width of said opening being slightly greater than the diameter of the coin, 100 of an ejector movable within and guided by such opening having a beveled tooth forming the support for a coin, a finger carried by the ejector in line with such shelf, the space between said finger and ejector being designed 105 to accommodate the articles of merchandise, and a second casting pivotally secured to the first-mentioned casting and having a coin inlet and passage-way opening above said wall, as set forth.

5. The combination with the casting having a supporting-shelf formed with an opening and a beveled wall, of an ejector movable within such opening having a beveled tooth forming the support for a coin, and a finger carried by 115 the ejector in line with said shelf, the space between said finger and ejector being designed to accommodate the articles of merchandise, a second casting pivotally secured to the first-mentioned casting and having a coin inlet and 120 passage-way opening above said wall, and a supply-chute having a cross-piece opposite the lower portion of said beveled wall, as set forth.

6. In a coin-controlled vending-machine, a 125 supporting-shelf having an opening, an ejector having an upright plate movable in said opening and a coin-support beneath but in line

with such opening, the coin resting on such support being in engagement with the side edges of the opening while in contact with the article to be ejected and between such article and said plate, such coin being dependent upon such article for its retention on such support, as set forth.

In testimony whereof I have signed this specification in the presence of two subscribing witnesses.

MAURICE HOFHEIMER.
